FILING EQUIPMENT

Emil Kern, Long Island City, N. Y., assignor to
 Acco Products, Inc., Long Island City, N. Y., a
 corporation of New York

Application December 31, 1938, Serial No. 248,693

5 Claims. (Cl. 45-2)

The invention relates to filing equipment and more particularly to filing units and means for mounting said units in a cabinet or the like.

Large drawings, maps, samples, and the like, are not easily filed and maintained accessible in some types of filing equipment because often such drawings, maps, etc., must be laid flat one upon another. Other known types of filing equipment, such as those disclosed in Patents #1,867,158 and #1,867,159, consist of a filing cabinet, or the like, having removable filing units therein from which the drawings, maps, or the like are suspended. The present invention embodies improvements on the latter type of filing equipment.

It is, therefore, an object of the invention to provide filing equipment with simple, efficient and inexpensive filing units to facilitate suspension or vertical filing.

Another object is to provide a novel frame structure for a filing cabinet or the like which will accommodate many or a few vertical filing units.

Another object is to provide a vertical filing unit with novelly mounted and constructed hanger arms or rods arranged to receive slidable suspension members.

Another object is to provide inexpensive suspension members slidable on the hanger arms or rods, which embody novel structural details.

The foregoing and such other objects of the invention as will appear hereinafter, will be more readily understood from a perusal of the following specification, in which reference will be made to the accompanying drawings, wherein:

Fig. 1 is a perspective view of a cabinet, partially broken away to show one embodiment of the improved filing units.

Fig. 2 is a fragmentary vertical sectional view of the cabinet.

Fig. 3 is a fragmentary plan view showing the hanger rod mounting.

Fig. 4 is a fragmentary elevational view taken substantially along line 4-4 of Fig. 2.

Fig. 5 is a fragmentary elevational view similar to Fig. 4, showing a modified form of filing unit.

Fig. 6 is a fragmentary sectional view taken on line 6-6 of Fig. 5.

Fig. 7 is a fragmentary view similar to Fig. 6, showing a modified form of filing unit.

Fig. 8 is a fragmentary sectional view similar to Fig. 6, showing a modified structure.

Fig. 9 is a vertical sectional view taken on line 9-9 of Fig. 8.

Fig. 10 is a fragmentary sectional view similar to Fig. 8, showing another modified form of filing unit.

Fig. 11 is an elevational view taken substantially along line 11-11 of Fig. 10.

Fig. 12 is a fragmentary sectional view showing a modified form of filing unit similar to that shown in Fig. 7.

Fig. 13 is a fragmentary sectional view similar to Fig. 6, showing a modified form of construction.

Fig. 14 is a fragmentary elevational view taken substantially along line 14-14 of Fig. 13.

Fig. 15 is a fragmentary rear elevational view showing a modified form of hanger rod support.

Fig. 16 is a fragmentary rear elevational view, similar to Fig. 15, showing another form of hanger rod support.

Fig. 17 is a sectional view similar to Fig. 13, showing a modified form of hanger rod and suspension member.

Fig. 18 is a fragmentary perspective view of a modified form of slidable suspension member.

Fig. 19 is an elevational view, partly broken away, showing another form of slidable suspension member.

Throughout the description, like numerals identify corresponding parts in the drawings.

The invention is best illustrated as shown mounted within a cabinet 11 having spaced apart vertical frame members 12, one preferably adjacent each corner thereof. It is obvious, however, that the vertical frame members 12 may constitute a part of an open frame work which may readily be set up in a cabinet or other suitable enclosure, such as for example, a vault or closet.

The vertical frame members 12 provide a mounting for spaced apart filing unit supports 13 and 14, as best illustrated in the embodiment disclosed in Figs. 1 to 4, inclusive. Each support 13 and 14 extends transversely of the cabinet 11 and each is detachably secured at its ends, preferably below the top wall of the cabinet, to the associated frame members 12 by bolts 15. The vertical frame members 12 preferably are provided with uniformly spaced holes 16 along their entire length, whereby the supports 13 and 14 may be adjustably secured at any required elevation. In the cabinet shown (Fig. 1) only one set of supports 13 and 14 is illustrated, but it is apparent; that, should the sheets or other contents 17, mounted in the cabinet, not require the full height, or should a larger cabinet be available, a second set of supports could be at-

tached to the vertical frame members 12, just below the bottom edge of the sheets suspended from the upper filing unit supports.

The horizontal supports 13 and 14 afford a mounting for a plurality of novelly constructed filing units, each of which comprises a hanger arm or rod 18 and a suspension member 19, slideable thereon, to which the file contents, such as sheets 17, is secured. In the embodiment shown in Figs. 1 to 4, inclusive, the rod 18 has a down-turned portion 21 (Fig. 2) at its rear end and an oval-shaped portion 22 at its forward end. The down-turned portion 21 is inserted through an elongated hole 23 (Fig. 3) provided therefor in the horizontal flange of the rear filing unit support 14, whereby a loosely fitted pivotal mounting is provided to enable the rod to tilt downwardly sufficiently to dispose its free forward end 22 below the bottom edge of the front filing unit support 13. The degree of tilting is limited by abutment of the bottom end of portion 21, preferably, with the vertical wall of the rear support 14.

While the rod 18 is in its downwardly tilted or forwardly inclined position, the suspension member 19 may be freely slid onto or withdrawn from the rod. Each suspension member 19 preferably constitutes a stiff sheet, such as metal, heavy cardboard, fabric, composition, or the like. The sheet is folded longitudinally, substantially U-shaped, to provide spaced apart side walls, preferably of uniform depth. Said walls preferably are apertured, as at 24 (Fig. 18) to readily receive the prongs of suitable fasteners 24a, whereby the sheets 17 are securely clamped and bound thereby, adjacent one edge, between the spaced apart suspension member walls. Obviously, other types of fastening means may be used, and if the files are made up in permanent form, rivets, staples or stitch binding may be employed.

It should be noted that the sheets 17 do not extend to the entire depth of the U-shaped member but; that, a space is maintained along the upper folded edge of said member to freely admit the hanger rod 18.

After a suspension member 19 has been slipped over the downwardly tilted rod 18, the oval-shaped forward end 22 of said rod is grasped and the rod is manually raised to carry said end into engagement with a hook-like formation 25, preferably formed in the vertical wall portion of the front support 13. The hanger rod is thus held in a substantially horizontal position and the suspension member 19 with its contents cannot be withdrawn. To remove the suspension member, the forward end of the rod 18 must be disengaged from the front support and the rod permitted to tilt downwardly, whereby the member 19 may be freely slid off after first being assisted past the slight shoulder formed by the oval-shaped portion. Accurate filing of the various suspension members 19 is facilitated by a suitable tab receptacle 26 on each member and, as at 27, on the front support, to receive index tabs. Accordingly, any suspension member withdrawn is readily returned to its proper place in the filing cabinet.

In Figs. 5 and 6, a structure substantially like that hereinbefore described is illustrated. In this instance, the front support 13a carries a plurality of spaced hooks 28, preferably formed of strip material, each to receive the free forward end of arm or rod 18.

The structure illustrated in Fig. 7 differs from the previously described arrangements in that the rod 18a is supported at its rear end only in the

5 rear support 14. The forward end of the slideable suspension member 19a has an upstanding hook 29. The hook is adapted to be engaged over the edge of an aperture 31 in the front support 13b, to retain the assembled filing unit horizontal. By providing a like hook at each end of the suspension member, said member may be reversed end for end.

10 In the device illustrated in Figs. 8 and 9, a channel 14a provides the rear support. As shown, the down-turned end 21 of the hanger rod 18 extends through appertures in the flanges. The aperture 23a, in the lower flange, is elongated to allow for tilting of the rod. The front support 13c also differs from those hereinbefore described in that it has a rearwardly extending flange suitably formed to provide a plurality of semi-circular sockets 32, each to receive and support the front end of one rod 18.

15 In the device illustrated in Figs. 10 and 11, the rear support 14b is apertured to receive the straight end of the hanger rod 18b. The front support 13d has hook-like formations 25a each to receive and support the front end of one rod 18b.

20 The structure illustrated in Fig. 12, is similar to that shown in Fig. 7. Here the front support 13e has a hook 33 which is engaged by a ring or eyelet 29a carried in the forward end of the suspension member 19b. The ring or eyelet 29a serves as a handle to facilitate sliding of the member 19 and, by providing one at each end of the member, said member is then reversible.

25 In the structure shown in Figs. 13 and 14, the rear end of the hanger rod 18c has a threaded reduced diameter 34 extending through an aperture in the rear support 14c and is retained loosely therein by a nut 35. The front support 13f carries a plurality of pivotally mounted hooks 36, one provided to engage and support the forward end of each rod.

30 The rear supports 14d, shown in Figs. 15 and 16, differ slightly from the showing in Fig. 13. In Fig. 15, a bayonet slot 37 is provided to receive the channeled end portion of the hanger rod 18d.

35 In Fig. 16, a substantially triangular shaped aperture 38 is provided to receive the rear end portion of the hanger rod 18e, which portion is suitably cut to detachably engage therein.

37 In the device as shown in Fig. 17, no front support is required. The hanger rod 18f has a groove 39, adjacent its end, like rod 18d of Fig. 15, to embrace the bottom edge of a rear support 14e. The rod 18f extends forwardly across the top edge of a second rear support 41 provided 40 forward of the support 14e. The co-acting edges of the two rear supports may be notched to insure uniform spacing of the rods. In this disclosure, a modified form of suspension member 19c is shown, which may consist of a single thickness of flat stock apertured adjacent one edge to receive the fasteners 24a. Its opposite longitudinal edge carries suitable eyelets or rings 42 for sliding engagement with the hanger rod 18f.

45 The suspension member 19d, illustrated in Fig. 18, differs from the other types shown, only in that the upper edge of its single wall is rolled over to provide a continuous tubular channel 43 for sliding on the hanger d rod.

50 In Fig. 19, the suspension member 19e has tubular rod receiving portions 43a struck from one face thereof, preferably at regular intervals, throughout its length.

55 The filing equipment described provides a simple, inexpensive, compact and convenient fil-

ing system. It may be employed for storage of any number of sheets or the like, up to the full capacity of the space afforded. The filing units may consist of any of the various suspension members illustrated, associated with any one of the various types of hanger rods and supporting means applicable to such interchanging.

It is to be understood; that, the disclosures herein are illustrative rather than restrictive; and that, various changes may be made in the detail structure of the various parts, hence it is not desired to be limited to the precise structural details shown, but only insofar as may be required by the scope of the appended claims.

I claim:

1. In a filing device, a pair of vertically adjustable supports, a plurality of substantially horizontally extending rods mounted loosely at one end in one of said supports, means in the other support each to receive and support the free end of one of said rods, the free ends of said rods being adapted to be disengaged from the supporting means, sheet suspension members one slidably on each rod and means on the free end of each rod to prevent inadvertent sliding of the suspension member off said rod while said end is disengaged.

2. In a filing device, in combination, a hanger arm having means at one end to provide a tiltable mounting for said end, an enlargement on the other end of said arm, an inverted U-shaped sheet suspension member slidable on said arm over said enlargement, means to engage the enlarged end of said arm to maintain it substantially rigid, the enlarged ends of said rods being adapted to be disengaged from said means, and means to limit tilting of said arm when said enlarged end is disengaged.

3. In a filing device, in combination, a support, an arm loosely mounted at one end in said support whereby it is free to tilt forwardly downwardly relative thereto, means to limit the amount of tilting, a sheet suspension member telescopically mounted on said arm, said member being slidable over the free end of said arm, means on the arm to prevent inadvertent sliding off of the suspension member while said arm is tilted, a second support, and means on said second support to co-act with said arm to maintain it substantially horizontally.
4. In a filing device, in combination, a support, an arm pivotally mounted in said support for movement through a substantially horizontal plane, said arm being adapted to tilt downwardly relative to said support, means to limit the amount of said tilting, a sheet suspension member telescopically mounted on said arm, said member being slidable over the free end of said arm, means to prevent inadvertent sliding of said suspension member off from said arm while the arm is tilted, a second support, and engageable means on said second support to maintain said arm substantially rigid horizontally.
5. In a filing device, in combination, a substantially horizontal arm mounted at each end in a support, a sheet suspension member telescopically associated with said arm, said arm being disengageable from one of its supports whereby it is free to tilt downwardly toward its free end to permit withdrawal and replacement of the suspension member, and means on said free end of the arm to prevent inadvertent sliding off of the suspension member while said arm is tilted.

EMIL KERN.
